(57) **CLAIM**

The ornamental design for a susceptor for semiconductor substrate supporting apparatus, as shown and described.

DESCRIPTION

FIG. 1 is a perspective view of a susceptor for semiconductor substrate supporting apparatus, showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is an enlarged view of a portion labeled, "FIG. 8," in FIG. 1; and, FIG. 9 is a cross-sectional view taken along line 9-9 of FIG. 8.

The even dashed broken lines shown in the drawings represent portions of a susceptor for semiconductor substrate supporting apparatus that form no part of the claimed design. The dashed-dot-dashed lines represent the boundary lines of the claimed design.
